UNITED STATES PATENT OFFICE

JULIUS KAHN, OF YOUNGSTOWN, OHIO

RIB-FORMING DIE

Application filed September 6, 1927. Serial No. 217,606.

The present invention relates to dies for making closed T-section ribs on sheet metal and particularly for making sheet metal material such as is disclosed in application, Serial No. 39,227, filed June 24, 1925, on Building construction, in the name of Julius Kahn.

Among the objects of the invention is to simplify the process of making this and similar material.

10 Another object is a die that is simple in construction and operation and that requires little attention to keep in proper condition.

Still other objects will readily appear to those skilled in the art upon reference to 15 the following description and accompanying drawings in which

Fig. 1 shows an end elevation the two part die open with a work piece in position to be formed.

20 Fig. 2 is a similar view of the die closed upon the work piece.

Fig. 3 is a perspective view of a work piece before forming and

25 Fig. 4 is a similar view of finished rib. As indicated the die is, as usual, in two parts, one being secured in suitable fashion to the plunger of a suitable press and the other to the stationary part.

In the present die, the stationary part is 30 merely an anvil or bed 20 having substantially a flat hardened insert 21 upon which the work piece 23 rests to receive the pressure of the moving member.

The movable portion of the die consists of 35 a body portion 30 provided with any suitable means (not shown) by which it is secured to the press plunger.

This body 30 is channeled to provide depending flanges 31 acting as stops for the 40 die jaws 32. These latter are L-shaped in section with the stem of the L formed into longitudinally extending substantially cylindrical male bearing members 33 adapted to coact with corresponding female bearing members 34, preferably lined with suitable bushings 35, provided in the body 30. The L-shaped jaws are therefore adapted to rock about the axes of the bearing portions 33.

45 These jaws 32 are provided with foot portions 40 extending toward the central plane

of the body and their opposed faces are shaped to produce the desired shaped sides of a rib. The feet 40 are also of such thickness that in closed position they rest against the under side of body 30, while the under side of the feet are substantially in the same plane with each other and with the bottom faces of flanges 31.

55 It is preferred to provide the feet 40 with hardened inserts 41 at their lower outer corners to provide against excessive wear at these points, and to extend the rear ends of the feet backward to form heels 42 acting as stops to limit the opening of the jaws.

60 Also carried by the body portion 30, in suitable sockets are plungers 50 having feet 51 adapted to press upon the feet 40 of the jaws 32 so as to force the latter open when the body 30 is lifted, suitable springs 52 being provided in the sockets.

65 The body 30 also carries in its under face along its center line, a hardened strip 55 adapted to press upon the top of the rib and suitably shape its upper surface.

70 In operating the die, the work piece 60, previously ribbed in the form shown in Figs. 1 and 3 in any conventional manner, is placed on the bed piece 21 as shown and the plunger portion forced down thereon to the position shown in Fig. 2. This causes the jaws 30 to rock inwardly and press together the sides of the rib while the piece 55 flattens the top, producing the rib form shown at 60^a in Fig. 4.

75 It is of course obvious that the opposed faces of jaws 32 and the under surface of strip 55 may be shaped to produce any desired rib form and such variation is contemplated.

80 It is also obvious that the die part may be of any desired length depending solely on the length of the press.

85 Now having described the invention and the preferred form of embodiment thereof, it is to be understood that the said invention is to be limited, not to the specific details herein set forth but only by the scope of the claims which follow.

90 I claim:-

95 1. A rib forming die comprising a movable and a stationary member, the former comprising a body, a pair of jaws carrying die

members and mounted in the working face of said body and adapted to be closed by striking the work piece when the two members are pressed together, a third die member fixed in said body between said jaws, and means in said body for opening said jaws upon separation of the members, said stationary member presenting a substantially flat surface offering no obstruction to movement of work thereover.

10 2. In a rib forming die, a movable and a stationary member, the former having a body portion having a longitudinally channeled working surface, a pair of jaws L-shaped in section hinged in said channel and having their opposed faces shaped to produce the desired lateral conformation of a rib and a fixed die portion between said hinged jaws shaped to produce the desired top conformation of the rib, and spring pressed plungers carried in said body portion on either side of said fixed die portion and tending to maintain said jaws in open position, said stationary member presenting a substantially flat working surface.
